UNITED STATES PATENT OFFICE.

HARRY H. SCHROYER, OF CHICAGO, ILLINOIS, ASSIGNOR TO DUNBAR MANUFACTURING COMPANY, OF CHICAGO, ILLINOIS, A CORPORATION OF ILLINOIS.

UNIFOLD CAR-DIAPHRAGM.

1,276,272.

Specification of Letters Patent. Patented Aug. 20, 1918.

Application filed April 22, 1915. Serial No. 23,102.

To all whom it may concern:

Be it known that I, HARRY H. SCHROYER, a citizen of the United States, and a resident of the city of Chicago, in the county of Cook and State of Illinois, have invented certain new and useful Improvements in Unifold Car-Diaphragms, and I do hereby declare that the following is a full, clear, and exact description of the same, reference being had 5 to the accompanying drawings, and to the numerals of reference marked thereon, which form a part of this specification.

This invention relates to a car diaphragm constructed of a single piece of fabric 15 formed or folded in such a manner as to form the legs as well as the top of the diaphragm.

It is an object of this invention to construct an expandible vestibule diaphragm 20 composed of a unitary strip of fabric folded to form the top and leg members of the diaphragm.

It is also an object of this invention to construct an expandible vestibule diaphragm 25 composed of a unitary strip of fabric folded or arched outwardly to form the legs of the diaphragm, and with the top member folded inwardly affording an outwardly concave trough at the top of the diaphragm.

30 It is also an object of this invention to construct a vestibule diaphragm wherein the fabric forming the legs is folded convexly outward and the top is folded convexly inward.

35 It is furthermore an important object of this invention to construct a unifold, one piece expandible vestibule diaphragm wherein a single strip of fabric is folded to afford leg members which are convex outwardly, and a top member which is convex inwardly, and provided with suitable reinforcing elements at the different lines of fold between the top and leg members.

40 It is finally an object of this invention to construct an improved type of unifold diaphragm which, by slight modification, may be constructed to afford an inclined or sloping top member to effectually shed water and other matter falling thereon.

50 The invention (in a preferred form) is illustrated in the drawings and hereinafter more fully described.

In the drawings:

Figure 1 is a side elevation of a diaphragm constructed according to the principles of my invention shown attached to the vestibule of a car, only a fragmentary portion of which is shown. 55

Fig. 2 is a vertical section taken on line 2—2 of Fig. 1. 60

Fig. 3 is a vertical section taken on line 3—3 of Fig. 2, with parts shown in elevation.

Fig. 4 is a detail section taken on line 4—4 of Fig. 2. 65

Fig. 5 is a fragmentary top plan view at the junction of the top and one of the leg members of the diaphragm.

Fig. 6 illustrates a modified connection between the side and top members taken on line 6—6 of Fig. 7. 70

Fig. 7 is an exterior view thereof.

Fig. 8 is a view similar to Fig. 2, of a modified form of device, shown broken away.

Fig. 9 is a fragmentary side view thereof 75 at the upper end of the diaphragm.

Fig. 10 is a section taken on line 10—10 of Fig. 8, illustrating the fabric prior to being folded into the trough shape shown in Fig. 9. 80

As shown in the drawings: The diaphragm consists of a top member 1, and leg members 2 and 3, respectively, which are formed from a single strip of fabric by folding the leg members convexly 85 outward and the top member convexly inward to afford a trough. The fabric at the lower end of the legs 2 and 3, is turned upwardly, as indicated by the reference numeral 4, around the interior of said legs to 90 reinforce the same at this point. At the junction between the arched or outwardly concave troughing strip 1, which affords the top member of the diaphragm, and the outwardly convex arched portion of the fabric forming the legs 2 and 3, thereof, are stitched reinforcement members 5, which serve to prevent breaking of the fabric at this point, and to assist further in weatherproofing the connection. The inner edges 100 of the legs of the diaphragm are attached to the car by means of metal strips 6, and the outer edges of the top member 1, are likewise held attached to the car body by means of metal strips 7. The opposite corresponding edges of said top and leg members are

95

100

105

secured to a face plate 8, by means of metal attaching strips denoted by the same corresponding reference numerals 6 and 7.

In the modified form of device illustrated in Figs. 6 and 7, I have shown a slot 9, cut in the junction between the top member 1, and leg member 2 or 3, as the case may be, which is surrounded by a strip of fabric 10, stitched thereto to reinforce the same and 10 prevent fraying of the rough edges, and the reinforcing member in the present instance denoted by the reference numeral 11, is then stitched thereover in a manner similar to the method of attachment of the reinforcement members 5, hereinbefore referred to.

In the modified form of device illustrated in Figs. 8, 9 and 10, I have shown a top member having a rib 12, extending transversely thereacross at the middle portion thereof, 20 formed by gathering the fabric and stitching the same, as clearly shown in sectional view in Fig. 8, so as to constrict the top member, causing the same to incline upwardly toward its middle, thus affording a 25 watershed.

The attaching bars by which the top member is attached to the vestibule of the car and to the face plate 8, are also angled, being denoted by the reference numerals 13 30 and 14, to further assist said top member in maintaining its warped form of inclination downwardly on each side of the middle toward the leg portions of the diaphragm. The construction of the modified form is 35 otherwise identical with that described in Figs. 1 to 5 inclusive.

The operation is thought to be obvious, but attention is called to the fact that this type of diaphragm may be constructed very 40 cheaply and easily adapted to all types of cars. Due to the fact that the leg members are folded convexly outward, a wide entrance-way between the leg members is thus obtained, and the depth of fold of the leg 45 members may be increased to a great extent for the purpose of permitting greater expansion of the diaphragm without in any way decreasing the width of the entrance-way between the leg members. The dia- 50 phragm may readily be expanded on one side only, as under such conditions to which

the same is subjected when a car is rounding a curve without in any way straining or unduly warping the fabric of the diaphragm.

I am aware that various details of construction may be varied through a wide range without departing from the principles of this invention, and I therefore do not purpose limiting the patent granted otherwise than necessitated by the prior art.

55

60

I claim as my invention:

1. A mono-fold diaphragm of the class described comprising a unitary strip of fabric shaped to form the top and leg portions of the diaphragm, the top portion curved convexly inwardly, a transverse rib formed in the top portion causing the top inclining from the middle downwardly toward the ends, said leg portions curved convexly outward.

2. In a device of the class described a mono-fold car diaphragm comprising a unitary strip having outward convex leg folds, an inward convex top fold, and a member folded around the corner formed by the 75 legs and top and secured thereto.

3. In a device of the class described a mono-fold diaphragm comprising outwardly convexed legs, an inwardly convexed top, means for drawing the top at the center 80 upwardly causing the same to slope downwardly to the ends, and reinforcing members secured at the junction of the legs and top.

4. In a device of the class described a 85 mono-fold diaphragm comprising a unitary strip of fabric bent to form the outwardly convexed legs and inwardly convexed top, and transverse reinforcing members secured at the junction of the legs and top.

5. A mono-fold diaphragm comprising outwardly convexed U shaped legs joined by an inwardly convexed U shaped top disposed in the same plane.

In testimony whereof I have hereunto 95 subscribed my name in the presence of two subscribing witnesses.

HARRY H. SCHROYER.
